[57] CLAIM

The ornamental design for an outdoor heat exchanger cabinet for an air conditioning unit, as shown and described.

DESCRIPTION

FIG. 1 is a top, right side and front perspective view of an outdoor heat exchanger cabinet for an air conditioning unit, showing our new design;

FIG. 2 is a top plan view thereof;

FIG. 3 is a right side elevational view thereof, the left side being a mirror image; and

FIG. 4 is a front elevational view thereof, the rear being a mirror image.

FIG. 1

FIG. 2

FIG. 4

FIG. 3
